PUMP

Marvin W. Ditto, New York, N. Y., assignor to
Emulsions Process Corporation, a corporation
of Delaware

Application September 17, 1938, Serial No. 230,480

6 Claims. (Cl. 103—41)

The present application is a continuation-in-part of my application Serial No. 197,910 filed March 24, 1938.

This invention relates to improvements in pumps and more particularly to proportioning or metering pumps.

The primary purpose of the invention is to provide a high pressure pump which will give a steady, non-pulsating movement to the pumped fluids, such as oil and/or water.

A further object is to supply a pump of smaller size than other pumps now on the market for similar purposes but adapted to deliver like volumes under substantially the same pressures as the larger pumps.

A further object is to furnish a high pressure proportioning pump, the moving parts of which will produce less wear and the elements of which will make repairs easy.

Another object is to supply a pump having two sets of plungers and adjustable means for varying the amount of liquid pumped by either set of plungers.

With the foregoing objects outlined and with other objects in view which will appear as the description proceeds, the invention consists in the novel features hereinafter described in detail, illustrated in the accompanying drawings and more particularly pointed out in the appended claims.

In the drawings:

Fig. 1 is a longitudinal sectional view partly in elevation of approximately one-half the pump.

Fig. 1A is a similar view of the other half.

Figs. 2 and 3 are transverse sectional views taken respectively on the lines 2—2 and 3—3 of Fig. 1A.

Fig. 4 is a transverse vertical sectional view taken on the line 4—4 of Fig. 1A.

Referring to the drawings, 5 designates a tubular medial casing having end closure plates 6 and 7 secured in position by screws 8 (Fig. 2). Bolts 9 project from the end plates through spacing sleeves 10 and through collars 11, the latter being integral with cylinder blocks 12 and 13. The sleeves 10 serve to space the plates 6 and 7 respectively from the blocks 12 and 13, and nuts 14 and washers 15 are mounted on the bolts to secure the parts together.

The outer ends of the cylinder blocks are secured by screws 16 (Fig. 3) to cylinder heads 17 and 18, and each head is provided with radial ports 19. Each of these ports contains a tubular cage 20 that is removably secured in place by a plug 21 having threaded engagement with the

cylinder head. An intake manifold passageway 22 is provided in each cylinder head, and by means of ports 23, the passageway communicates with the interior of the cages 20. A valve seat 24 is associated with each of the ports 23 and cooperates with a valve head 25. The valve heads have stems 26 that are guided by sleeves 27 arranged in the cages, and each valve head is yieldingly urged toward its seat by a coil spring 28.

Each cylinder head also has an outlet or discharge passageway 29 that communicates with the interior of the cages by means of ports 30.

Each cage is provided with a valve seat 31 that cooperates with an outlet valve head 32, the latter being arranged to reciprocate radially of the cylinder head and being yieldingly urged toward its seat by a coil spring 33 which bears against the plug 21.

Each cylinder block is provided with a set of bores 34 which communicate with the interior of the valve cages by means of ports 35 and 36 provided respectively in the valve cages and in the cylinder heads. A spider 37 forming part of each cage extends across the port 35 thereof in order to guide the stem of the intake valve.

Sets of plungers or pistons 38 and 39 are arranged for reciprocation in the bores of the blocks 12 and 13, and each plunger is provided at its outer end portion with a cam shaped peripheral recess 40 for a purpose hereinafter described.

Packing rings 41 surround each plunger and are held in place by a threaded gland 42 that is screwed into the cylinder block.

The means for reciprocating the plungers consist of a rotatable main shaft 43 that may be driven by any suitable prime mover. The shaft is journaled in combined radial and thrust bearings 44, 45 and 46 arranged respectively in the cylinder head 18 and closure plates 7 and 6. The shaft extends through the center of the cylinder block 13 and is arranged parallel to the plungers.

An annular cam 47 is fixed to the inner end portion of the shaft and is arranged to rotate in the casing 5. The cam acts on rollers 48, journaled on pins 49 which serve to secure guide and connecting elements 50 to the inner ends of each pair of plungers, formed by aligned plungers of the two sets 38 and 39. Dowel pins 51 also connect the plungers to the guide elements 50 and 51 act to reinforce the joint formed by the pins 49.

It will be obvious from the foregoing that the turning of the cam 47 will cause the plungers to reciprocate in the bores of the cylinder blocks so that liquid will be drawn into the

cylinder through the ports 23 and past the valves 25 and will be ejected through the valve seats 31 and past the valves 32.

For purposes of inspection, repair or replacement and for guiding the connecting elements 50, it will be noted especially from Fig. 4 that the medial casing 5 is provided with a radially disposed series of ports 52 corresponding in number to the number of elements 50 and that each port is closed by a removable cover 53 having a V-shaped inner surface 54 cooperating with a complementary surface on each of the elements 50. It will be clear from Figs. 1, 1A and 4 that when a cover plate is removed, the guide element 50 which is associated with the same may be readily reached for removal, as well as the rollers 48 and pins 49 which are associated with that particular plate.

For proportioning purposes the plungers 38 and 39 are not only mounted for reciprocation but also for rotary movement. To permit this, each plunger is made in two sections 55 and 56 (Fig. 1) which are joined together by a swivel connection 57 that permits rotation of the section 55 about its axis. The swivel joint preferably includes an anti-friction bearing 58 that is positioned between shoulders 59 and 60 arranged respectively on the sections 55 and 56. The anti-friction bearing is held in position and the sections 30 are held together by half collars 61, secured to one another by bolts 62. A small gear 63 is fixed to each piston 38, and these gears mesh with a larger gear 64 which is positioned between them and fixed to a manually operated shaft 65, journalled in a sleeve 66 of the cylinder block 12, and a bearing 67 formed in the closure plate 6. The shaft 65 is co-axial with the main shaft 43 and is provided at its outer end with a hand wheel 68. When the hand wheel is turned, the gear 64 turns the gears 63 as well as the sections 55 of the pistons 38. This results in rotary adjustment of the recesses 40 relatively to by-pass passageways 69 that place the bores of the cylinder block 12 in communication with the intake conduit 22. With such a construction, if the regulating wheel 68 is turned to rotate the plungers more than ninety degrees from the base lines 40a of the recesses 40, the by-pass passageways 69 will be closed and the cylinders will always 50 discharge during the full travel of the stroke of the plungers. However, if the plungers are rotated to a position where the recesses communicate with the by-passes; during the discharge stroke, the passageways 69 will remain 55 open a period of time equal to the time required for the plunger to travel the distance from its outer end to the inclined edge 40b of its recess, and consequently the plungers will not pump the full amount during each discharge stroke. Therefore, by setting the relative position of the pistons, any proportion of water, oil or other liquid 60 can be obtained from one set of plungers with respect to the other. By way of further explanation, it will be observed that the plungers 39 are also provided with gears 63a that mesh with a larger gear 64a which surrounds the main shaft 43 and is fixed on a rotatable sleeve 64b carried by and projecting from the cylinder block 13. Here also each of the recesses 40 of the plungers 70 39 cooperates with a by-pass passageway 69a that leads from the bore portion of the block 13 to the intake conduit 22 of the cylinder head 18.

The gear 64a is rigidly united with a sprocket wheel 70 which is turned by means of a sprocket chain 71, the latter being actuated by a sprocket

wheel 72, that is rotatably mounted on a shaft 73 journalled in a sleeve 74, that is supported by the closure plates 6 and 7. The end of the shaft 73 opposite that where the sprocket wheel 72 is located, is provided with a second sprocket 5 wheel 75, also rotatably mounted on the shaft 73. Both sprocket wheels, however, may be locked or fixed to the shaft by providing one end of the shaft with a nut 76 and at its opposite end with a threaded hand wheel 77. When the hand wheel is unscrewed slightly, either sprocket wheel may be turned relatively to the shaft, and as will hereinafter be explained, this will permit the plungers 38 to be rotatably adjusted relatively to the plungers 39 or vice versa, so that the recesses 40 of one set of plungers may be positioned differently from the recesses of the other set of plungers. Of course, when the wheel 77 is tightened, the sprocket wheels 72 and 75 will be locked to the shaft 73 and then if the sprocket 20 wheel 75 is turned, it will cause turning of the plungers 39. The sprocket wheel 75 is actuated by a sprocket chain 78 driven by a sprocket wheel 79 that is rigidly united with the gear 64. Manifestly, if the wheel 68 is turned and the hand wheel 77 has been tightened, all of the plungers will be rotated in unison for simultaneous adjustment to take care of the proportioning desired. Depending upon the positions of the recesses 40, the amount of liquid displaced 30 during the stroke of the pump is regulated, that is, if the recesses are disposed to by-pass the liquid for 50% of the stroke, then displacement of the piston in that position is only 50% of the volume. Of course, the relative proportions of 35 liquids displaced at the opposite ends of the pump can be regulated in the manner heretofore described. The construction is such as to permit a difference in the proportioning of two liquids (handled by opposite ends of the pump) from 40 0 to 50%.

In operation, if water is admitted to one set of cylinders at one end of the pump and oil into the other set at the opposite end, and the diameter of the cylinders and the length of the plungers are equal in both instances, the pump would discharge 50% water and 50% oil. Such proportioning can be changed by varying the diameter of either set of pistons and cylinders relatively to the other so as to obtain any desired ratio. 50 However, I prefer to vary the proportions by the piston-adjusting means illustrated in the drawings and described above. Of course, total output of the pump can be controlled by varying the speed of the shaft 43. 55

Primarily, this design of pump is useful and necessary where it is essential that accurate proportions of different kinds of oil, oil and water or other liquids must be measured, and where it is impractical to regulate such mixtures by the adjustment of valves. The pump acts as a metering device as there is positive displacement accurately measured by the speed with which the cam 47 is rotated. The pump illustrated operates satisfactorily to produce 3000 pounds pressure 65 per square inch, and translates a high motor speed (without the use of gears) into reciprocal motion through the cross head guide elements 50 and rollers 48, with a minimum of vibration or shock. The design of this pump is unique 70 because of the fact that reciprocal motion of positive displacement pistons is obtained without the use of wobble plates, gears or like mechanical means. It is very efficient because the rotary motion is translated into reciprocal motion by a 75

cam having a progressively inclined plane in constant contact with the rollers at both faces of the cam. Due to this construction, it is unnecessary to have special means of applying power as

5 anything that will rotate shaft 43 will result in pumping action on the reciprocating pistons. By this means, with constant inclined plane developed on an annular surface, there is progressive application of power without shock.

10 The pump has tremendous capacity at high pressures in a confined space due to the translation of rotary motion into reciprocal motion, short stroke and the ability to absorb both thrust and radial loads in the central casing 5

15 carried on the anti-friction bearings 45 and 46. As compared to other pump equipment for similar purposes, there is complete elimination of gears, yokes, etc., in giving variable strokes, etc. With suitable materials used for construction,

20 extremely high pressures can be produced without pulsation, and the equipment is so designed that it is easy to maintain in repair.

In a pump according to my invention, as there is a progressive motion of the operating cam 25 around its axis, there are four cylinders on each side that are on the suction cycle and four discharging on the pressure side at each end of the pump, and as there are sufficient cylinders around the axis at each end of the pump, pulsation is eliminated in the overlapping of the discharge strokes.

30 Instead of operating the wheel 68 manually, it will be obvious that such wheel might be actuated automatically by any suitable means in order to change the proportions of the liquids pumped. Of course, the apparatus need not be used for proportioning purposes, and it may be employed as a straight pump as it is particularly adapted for procuring very high hydraulic pressures, and can therefore be used as a means for varying the amount of load carried by hydraulic pressure.

35 The face of the operating cam and its cooperating roller in each instance are developed at the proper angle so that the maximum and minimum radii of the rollers travel at the same rate of speed along the space of the line contact between rollers and the cam thereby reducing friction and wear.

40 Instead of operating the units at the opposite ends of the pump in an opposed piston manner, it is manifest that such units may be driven separately by a separate motor. I prefer, however, to build the pump as of opposed piston type, as such construction is cheaper and does not require such heavy thrust bearings as separate units.

45 From the foregoing it will be appreciated that the units may be separately built and powered and such a construction makes a very flexible pump as the proportions may be varied by the speed of the individual motors, whereas in the opposed piston type the output of one unit must be varied by some device such as illustrated, as 50 both units are driven at the same speed by a common shaft.

55 I wish it distinctly understood that my improved pump as described and illustrated is in forms which I desire to construct and that 60 changes and variations may be made as may be convenient or desirable without departing from the salient features thereof, and I therefore intend the following claims to cover such modifications as naturally fall within the lines of the 65 invention.

What I claim and desire to secure by Letters Patent is:

1. A proportioning pump comprising casing means provided with a plurality of series of bores, valve-controlled intake and discharge passageways communicating with one series of bores, other valve-controlled intake and discharge passageways communicating with the other series of bores, each intake passageway and discharge passageway being common to the series of bores 5 with which they communicate, a first set of plungers having rotatable portions arranged to rotate and reciprocate in one series of bores, a second set of plungers having rotatable portions arranged to reciprocate and rotate in the other 10 series of bores, each plunger having a peripheral recess communicating with the bore in which the plunger reciprocates, a by-pass connecting each bore with the intake passageway with which it is associated and adapted when the plunger in 15 that bore is in a certain position to pass fluid from the bore to the intake passageway, means for reciprocating the plungers, and selective means connecting the rotatable portions of one set of plungers to the rotatable portions of the 20 other set of plungers whereby the rotatable portions of one set of plungers may be turned in unison with the rotatable portions of the plungers of the other set, or the rotatable portions of the 25 plungers of either set may be turned relatively 30 to the rotatable portions of the other set.

2. A proportioning pump comprising casing means provided with oppositely disposed series of bores, valve-controlled intake and discharge passageways communicating with one series of 35 bores, other valve-controlled intake and discharge passageways communicating with the other series of bores, each intake passageway and discharge passageway being common to the series of bores with which they communicate, a first set of plungers having rotatable portions arranged to rotate and reciprocate in one series of 40 bores, a second set of plungers having rotatable portions arranged to reciprocate and rotate in the other series of bores, each plunger having a peripheral recess communicating with the bore in which the plunger reciprocates, a by-pass connecting each bore with the intake passageway with which it is associated and adapted when the plunger in that bore is in a certain position to pass fluid from the bore to the intake passageway, means for reciprocating the plungers, common means for turning the rotatable portions 45 of the plungers about their axes, and means operatively connected with the last-mentioned means to turn the rotatable portions of one set of plungers relatively to the other set of plungers to vary the volume of fluid pumped by one set of plungers relatively to that pumped by the other set of plungers.

3. A proportioning pump comprising casing means provided with oppositely disposed series of bores, valve-controlled intake and discharge passageways communicating with one series of bores, other valve-controlled intake and discharge passageways communicating with the other series of bores, each intake passageway and discharge passageway being common to the series of bores with which they communicate, a first set of 55 plungers having rotatable portions arranged to rotate and reciprocate in one series of bores, a second set of plungers having rotatable portions arranged to reciprocate and rotate in the other series of bores, each plunger having a peripheral recess communicating with the bore in which the plunger reciprocates, a by-pass 60

65

70

75

connecting each bore with the intake passageway with which it is associated and adapted when the plunger in that bore is in a certain position to pass fluid from the bore to the intake passageway, means for reciprocating the plungers, first gears fixed to the rotatable portions of each set of plungers, second gears meshing with the first gears, and means operatively connecting said second gears whereby the rotatable portions of both sets of plungers may be turned in unison or the rotatable portions of the plungers of one set may be turned relatively to the other set of plungers.

4. A proportioning pump comprising casing means provided with oppositely disposed series of bores, valve-controlled intake and discharge passageways communicating with one series of bores, other valve-controlled intake and discharge passageways communicating with the other series of bores, each intake passageway and discharge passageway being common to the series of bores with which they communicate, a first set of plungers having rotatable portions arranged to rotate and reciprocate in one series of bores, a second set of plungers having rotatable portions arranged to reciprocate and rotate in the other series of bores, each plunger having a peripheral recess communicating with the bore in which the plunger reciprocates, a by-pass connecting each bore with the intake passageway with which it is associated and adapted when the plunger in that bore is in a certain position to pass fluid from the bore to the intake passageway, means for reciprocating the plungers, first gears fixed to the plungers of each set, second gears meshing with the first gears, common means connecting said second gears whereby the turning of one of the second gears will cause simultaneous rotation of the rotatable portions of all of the plungers, and means operatively connected with the last-mentioned means to turn the rotatable portions of one set of plungers relatively to the other set of plungers to vary the volume of fluid pumped by one set of plungers relatively to that pumped by the other set of plungers.

5. A proportioning pump comprising casing means provided with oppositely disposed series of bores, valve-controlled intake and discharge passageways communicating with one series of bores, other valve-controlled intake and discharge passageways communicating with the other series of bores, each intake passageway and discharge passageway being common to the series of bores with which they communicate, a first set of plungers having rotatable portions

arranged to rotate and reciprocate in one series of bores, a second set of plungers having rotatable portions arranged to reciprocate and rotate in the other series of bores, each plunger having a peripheral recess communicating with the bore in which the plunger reciprocates, a by-pass connecting each bore with the intake passageway with which it is associated and adapted when the plunger in that bore is in a certain position to pass fluid from the bore to the intake passageway, means for reciprocating the plungers, manually controlled common means for turning the rotatable portions of the plungers about their axes, and manually controlled means operatively connected with the last-mentioned means to turn the rotatable portions of one set of plungers relatively to the other set of plungers to vary the volume of fluid pumped by one set of plungers relatively to that pumped by the other set of plungers.

6. A proportioning pump comprising casing means provided with oppositely disposed series of bores, valve-controlled intake and discharge passageways communicating with one series of bores, other valve-controlled intake and discharge passageways communicating with the other series of bores, each intake passageway and discharge passageway being common to the series of bores with which they communicate, a first set of plungers having rotatable portions arranged to rotate and reciprocate in one series of bores, a second set of plungers having rotatable portions arranged to reciprocate and rotate in the other series of bores, each plunger having a peripheral recess communicating with the bore in which the plunger reciprocates, a by-pass connecting each bore with the intake passageway with which it is associated and adapted when the plunger in that bore is in a certain position to pass fluid from the bore to the intake passageway, a series of cross heads, each cross head having one of its ends connected to a plunger of one set and its opposite end connected to a plunger of the other set, means operatively connected to said cross heads for reciprocating the plungers, and selective means connecting the rotatable portions of one set of plungers to the rotatable portions of the other set of plungers whereby the rotatable portions of either set of plungers may be turned in unison with the rotatable portions of the plungers of the other set, or the rotatable portions of the plungers of either set may be turned relatively to the rotatable portions of the other set.

MARVIN W. DITTO. 55
